2. The method of preparing a compound of the structure

wherein R_4 and R_5 are alkyl radicals having up to six carbon atoms which comprises heating at a temperature above about 40° C . a compound of the structure

in the presence of water and sodium hydroxide.

3. The method of preparing a compound of the structure

wherein R_4 and R_5 are alkyl radicals having up to six carbon atoms which comprises heating at a temperature above about 40° C . a compound of the structure

in the presence of water and magnesia.

4. The method of preparing N,N -diethyl α -chloroacetamide which comprises heating at the reflux temperature N,N -diethylcarbamyl chloromethylene triphenylphosphorane in an aqueous system in the presence of sodium carbonate.

5. The method of preparing N,N -dipropyl α -chloroacetamide, which comprises heating at the reflux temperature N,N -dipropylcarbamyl chloromethylene triethylphosphorane in an aqueous system in the presence of an alkali metal hydroxide.

10. The method of preparing N,N -diallyl α -chloroacetamide which comprises heating at the reflux temperature N,N -diallylcarbamyl chloromethylene trimethylphosphorane in an aqueous system in the presence of calcium carbamate.

15. The method of preparing N,N -dimethyl α -chloroacetamide which comprises heating at the reflux temperature N,N -dimethylcarbamyl iodomethylene triphenylphosphorane in an aqueous system in the presence of potassium hydroxide.

20. The method of preparing N,N -di-*n*-butyl α -chloroacetamide which comprises heating at the reflux temperature triphenyl N,N -di-*n*-butyl-carbamyl chloromethylene tricyclohexylphosphorane in an aqueous system in the presence of sodium hydroxide.
